UNITED STATES PATENT OFFICE.

JACK D. SARTAKOFF, OF NEW YORK, N. Y.

SANITARY ATTACHMENT FOR TELEPHONES.

1,354,780.

Specification of Letters Patent.

Patented Oct. 5, 1920.

Application filed June 14, 1918. Serial No. 289,949.

To all whom it may concern:

Be it known that I, JACK D. SARTAKOFF, a citizen of Russia, residing in the city of New York, borough of Manhattan, county 5 and State of New York, have invented a certain new and useful Sanitary Attachment for Telephones, of which the following is a specification.

This invention is a sanitary attachment 10 for a telephone, adapted to coöperate with the mouthpiece thereof in such manner as to maintain it in a sanitary and prophylactic condition.

It is commonly recognized by bacteriologists that the mouthpieces of telephones, and particularly those used in public stations, are a source of bacterial infection, and thus serve as a probable medium of transmitting various communicable diseases. 15 Moreover, various devices have been proposed with a view to overcoming or mitigating the evil, but the devices suggested, so far as I am aware, were of such character as to impair the effective operation of the 20 telephone, or possessed other inherent disadvantages which have precluded their employment.

The present invention overcomes the disadvantages specified, and others, and successfully solves the problem of maintaining a telephone mouthpiece in a thoroughly sanitary and antiseptic condition, and without, in any manner, detracting from the efficient 25 operation of the telephone.

From a broad standpoint, the invention embodies a member or device adapted to contain a suitable antiseptic or disinfectant and provided with suitable mechanical cleansing means, which device is adapted to 30 be inserted in the mouthpiece of the telephone when the latter is not in use, and to be readily withdrawn therefrom when desired. The act of inserting and withdrawing the device serves to simultaneously clean 35 the mouthpiece mechanically and disinfect the same, though, of course, the antiseptic and disinfecting action is taking place at all times when the device is positioned within the mouthpiece.

More specifically, the invention, from a structural standpoint, in its preferred form, embodies a perforated receptacle adapted to contain an antiseptic and coöperating brushes, or their equivalent, positioned exteriorly of said receptacle, the said receptacle being pivotally supported, preferably

to some part of the telephone, whereby the telephone operator may readily insert or withdraw the receptacle from the telephone.

Features of the invention, other than those described, as well as the advantages thereof, will appear from the hereinafter detailed description, taken in conjunction with the accompanying drawings.

The drawings illustrate one practical, and the preferred, embodiment of the invention, although it will be understood that the form shown is illustrative only, and not exclusive of the different ways in which the invention may be given expression.

Figure 1 shows a portion of the telephone in elevation, with the device or attachment of this invention applied thereto, the latter being shown in vertical section in full lines when occupying its position within the mouthpiece, and the dotted lines showing the position which the device assumes when withdrawn from the mouthpiece;

Fig. 2 is a front elevation of the device, on the line 2—2, Fig. 1; and

Fig. 3 is a view on the line 3—3, Fig. 1, looking in the direction of the arrows appearing thereon.

Referring to the drawings, 5 is the conventional telephone standard, 6 the transmitter, and 7 the customary mouthpiece, provided, as usual, with a perforated member 8.

The device of this invention embodies a perforated receptacle or chamber 9, preferably frusto conical in shape to conform with the inner contour of the mouthpiece, the interior of which perforated receptacle is adapted to contain a suitable antiseptic or disinfectant, indicated at 10, or a combination of such substances,—either in liquid, semi-liquid or solid form. In the event a liquid is employed, some absorbing medium, such as cotton or felt, will be used in the interior of the receptacle.

The exterior of the receptacle 9 is provided with brushes, indicated at 11, or equivalent means, for the purpose hereinafter specified. The front of the receptacle 9, and likewise the opening of the telephone mouthpiece 7 are closed by a plate or cover 12, provided with a screw-threaded boss 13 on to which the receptacle 9 is screwed and thereby supported within the telephone mouthpiece. The plate 12 is pivotally supported, as indicated at 14, to an arm or bracket 15, the lower end of which divides

into semi-circular members 16 which straddle the mouthpiece, and are secured in position thereon by means of a bolt 17. The lower end of plate 12 terminates in a handle 18 which may be readily grasped by the user of the instrument, thereby enabling the device to be readily inserted into the mouthpiece of the telephone or withdrawn therefrom by virtue of the pivotal movement of plate 12.

It will be noted that the antiseptic chamber 9 is loosely supported within the mouthpiece, *i. e.*, it has no connection therewith.

From the foregoing description, the operation and function of the device will be readily understood, but it may be referred to briefly as follows:

The receptacle 9 having been charged with a suitable antiseptic or disinfectant, as described, is mounted in position on the plate 12. The brushes 11, or their equivalent, assist not only in the distribution or dissemination of the antiseptic, but serve to cleanse the interior of the mouthpiece mechanically by virtue of their rubbing engagement therewith. The device is intended to be normally positioned within the mouthpiece, but a person using the telephone would simply withdraw the device, therefrom during the time the telephone is in use and reinset the device when he has finished using the telephone.

It will be understood that minor changes may be made in the device described, such as the substitution of equivalents, and that

certain features of the invention may be used without necessarily employing them all, the scope of the invention being commensurate with the appended claims.

Having, thus, fully described my invention, what I claim as new, and desire to secure by Letters Patent, is:

1. In a sanitary attachment for telephones, a movably mounted member adapted to seal and unseal the opening in the mouthpiece of a telephone, an antiseptic-carrying perforated receptacle supported by said member and movable to a position either within or without the mouthpiece, and brushes on the outer surface of said receptacle adapted to engage and clean the inner surface of the mouthpiece.

2. In a sanitary attachment for telephones, a yoke adapted to clamp on to, and be supported by the mouthpiece of a telephone transmitter, and a perforated receptacle, containing an antiseptic, pivotally associated with said yoke and movable to a position into and out of the mouthpiece, for the purpose of sterilizing the mouthpiece when the transmitter is not in use, and cleaning brushes mounted on the exterior of the receptacle and adapted to engage with the interior of the mouthpiece during the movement of said receptacle to mechanically clean the interior of the mouthpiece.

In testimony whereof, I have signed my name to this specification,

JACK D. SARTAKOFF.
